HAROLD V. McCORMICK, OF EVANSTON, ILLINOIS, ASSIGNOR TO WESTINGHOUSE ELECTRIC ELEVATOR COMPANY, A CORPORATION OF ILLINOIS

ELEVATOR-DOOR-OPERATING SYSTEM

Application filed May 6, 1931. Serial No. 535,477.

My invention relates to elevator-door-operating systems and more particularly to systems embodying motor carried by the cars, for operating the car doors, and a motor at each landing for operating the corridor door at that landing.

The object of my invention, in general, is to provide an elevator-door-operating system comprising apparatus that shall be simple and inexpensive to manufacture, install and maintain in operation.

A more specific object of my invention is to provide an elevator-door-operating system of the nature of that disclosed in the copending application of C. E. Ellis, Jr., and H. V. McCormick Serial No. 420,092, filed January 11, 1930, and assigned by mesne assignments to Westinghouse Electric Elevator Company, but in which the apparatus for controlling the operation of the door-operating motors may be conveniently located upon a switchboard in the pent house or in some other suitable location.

Another object of my invention is to provide an elevator-door-operating system in which the parts carried by the car for operating the car door shall be small in size and light in weight.

A further object of my invention is to provide an elevator-door-operating system in which the apparatus for controlling the door motors may be so constructed in the factory that it may be easily set up and adjusted to operate the doors in any installation in which it may be employed.

It is also an object of my invention to provide, in an elevator-door-operating system having individual door operators, for preventing the burning out of a motor when its door sticks or stalls.

Other objects of the invention will, in part, be obvious and will, in part, appear herein-after.

For an illustration of one of the various forms my invention may take, reference may be had to the accompanying drawings, in which:

Figure 1 is a vertical view, in section, of a portion of an elevator shaft, with an elevator car disposed therein.

Fig. 2 is a plan view of a controller for the motors for operating the elevator doors.

Fig. 3 is a view, taken on the line III—III of Fig. 2.

Fig. 4 is a diagrammatic representation of the circuits, motors and controller for operating the doors embodied in Fig. 1.

Fig. 5 is a diagrammatic representation of the connection of the field windings, and the armature windings of the motors shown in Fig. 4, and

Fig. 6 is a diagrammatic representation of the armature circuits in connection with the door checking and compensating resistors.

In Fig. 1, I have shown a plurality of vertical walls 1 comprising an elevator shaft 2 in which an elevator car 3 is suitably suspended by a cable 4.

The car 3 is provided with sliding door panels 5 and 6 that constitute a door or gate 7 which may be opened when passengers desire to enter or leave the car. The door panels are supported by means of a plurality of hangers 8 which travel upon a track 9 when the door is opened or closed.

The means for opening and closing the car doors 7 comprises a door-operating lever 11 pivotally mounted, by means of a bolt 12, upon a supporting base 13 carried on the roof of the car. The lower portion of the door-operating lever 11 extends downwardly, beside the car door, having its lower end connected to the front panel 5 by a link 14, and its middle portion connected to the rear panel 6 by a link 15. The position of the links is such that movement of the lever 11 to open or close the door will cause the panels 5 and 6 to reach their open or closed position simultaneously.

As shown, a motor 16 is mounted upon the supporting base 13 and is connected, through a worm gear 17, a crank 18 and a pitman 19, to the upper end of the door operating lever 11, in order that the door may be opened by operating the motor in one direction and closed by operating it in the opposite direction.

A corridor door 22, comprising a pair of sliding panels 23 and 24, is provided for closing the entrance to the corridor at each

floor landing. For convenience, the corridor doors have been shown for only two floors, but it is to be understood that a similar corridor door is disposed at each floor landing.

5 Each of the corridor doors 22 is provided with its own individual operating unit comprising a plurality of toggle levers 26, 27 and 28 and a motor 29.

10 One end of the toggle lever 26 is pivotally connected to the door panel 23 and its other end pivotally connected to the toggle lever 27 which is mounted pivotally, at its central portion, upon a bracket 21 secured to the rear edge of the door panel 24. The right-hand 15 end of the lever 27 is pivotally connected to the left-hand end of the lever 28, the right-hand end of which is pivotally mounted in a base plate 30 secured to the wall 1 of the elevator hatchway, so that a movement of the 20 toggle levers out of the straight-line position thereof will cause the door panels to move to their open positions, and movement of the levers into the straight-line position, thereof will cause the door to close.

25 The motor 29 for moving the toggle levers into and out of their straight-line position is hingedly mounted upon a bracket 32 that is secured to the wall of the hatchway. The armature shaft 33 of the motor is firmly connected to nut 34 which has a screw threaded interior aperture 35 in which is disposed the lower end of a screw threaded shaft 36. The upper end of the screw threaded shaft 36 is hingedly connected to one end of a lever 37 of 30 L-shape, the other end of which is pivotally connected to the stationary base plate 30 on the wall 1. The middle portion of the lever 37 is pivotally connected, by a link 38, to a downwardly extending projection 39 on the 35 toggle lever 28, so that, when the motor 29 rotates the screw nut 34 in a counter-clockwise direction, the screw threaded shaft 36 will be forced upwardly and thereby actuate the lever 37 and the link 38 to cause the toggle, 40 levers 28, 27 and 26 to break from their straight-line position and thus open the door 22.

50 If the motor 29 is rotated in a clockwise direction, the nut 34 will exert a downward pull on the shaft 35 to cause the toggle levers to assume their straight-line position, thereby moving the door panels 23 and 24 to close the corridor opening. If desired, a more detailed description of the mechanism for operating 55 the corridor doors may be obtained from my copending application Serial No. 473,851 filed Aug. 8, 1930 and assigned to Westinghouse Electric Elevator Co.

60 A switch CS is mounted in the car, whereby the car attendant may control the operation of the car.

65 Referring now to Fig. 4, which is a diagram of the circuits of my improved door-operating system, the armature windings and the field windings of the individual corridor-

door motors 29 and 29a are represented in the lower left-hand corner of the figure. At the right of the corridor motors, the car 3 is indicated in outline, together with the motor 10 for operating the car door.

70 The coil structure 43 of an inductor relay is carried by the car 10 in such position that it may successively cooperate with a plurality of armature members 45 disposed along the hatchway, one at each landing, for selectively preparing the circuits of the corridor-door motors at the landings for operation.

75 The inductor relay 43 on the car 10 is controlled by a relay 50, shown in the upper left hand corner of the drawings. The coil of the inductor control relay 50 is connected to the car-control system in such manner that the relay will be deenergized whenever the car is stopped and thereby close its contact members to complete a circuit for energizing the 80 inductor coil 43 while the car stops and remains at a landing. The energization of inductor relay 43 attracts the armature 45 at the selected landing and thereby closes its contact members *a* and *b* to prepare the circuit of the corresponding corridor door motor for operation.

85 In practice, the relay 50 is usually so connected to the car-control system that it will be deenergized to energize the inductor relay 43 when the car is still two or three feet away from the landing at which it is to stop, thereby insuring the preparation of the 90 circuit of the corresponding corridor-door motor for operation while the car is still a short 95 distance from the landing.

100 The circuits for the door motors extend upwardly to, and are controlled by, a door-opening relay OP and a door-closing relay CL. The operation of the relays OP and CL is controlled by a control relay 51 having a coil connected by a switch 49 to a source of 105 electric energy represented by supply conductors L3 and L4. The switch 49 is disposed to be operated by some part of the car-control system (not shown) in such manner that the relay 51 will be deenergized to operate the relay OP, to open the doors when the car stops, and energized to operate the relay CL to close the doors when the car starts 110 and to keep them closed while the car is running.

115 The circuit for the coil of the control relay 51 is also connected through the car switch CS in such manner that the relay will be energized to effect the closing of the doors as soon as the car attendant moves the car switch to start the car.

120 In practice, the control relay 51 is usually connected to the car-control system in such manner as to be deenergized to start the doors to open when the car is approximately 125 seven inches away from the landing at which it is to stop, thereby causing the doors to be fully open at the time the car finally stops.

5 A pair of manually operated switches 52 and 53 are provided for so connecting the motor circuits to the control apparatus that the corridor-door motors may be disconnected from the system without affecting the operation of the car-door motor; or the car-door motor may be disconnected without affecting the operation of the corridor-door motors.

10 10 A plurality of resistors R1, R2, R3 and R4 are provided for checking the speed of the door motors as the doors approach the end of their travel, in opening or closing, and a "safety resistor" R6 is provided for preventing the doors from attaining a dangerous speed at the center of their travel when they are closing the resistor R6 also reduces the motor torque if some one is caught in the doors.

15 20 In installing my door-operating system, it has often been difficult to so adjust the operating mechanism as to check the doors at the ends of their travel in such manner as to cause them to reach their final position simultaneously. For instance, the car door is frequently considerably lighter than the corridor door with which it operates. In such cases, the lighter door must be checked less than the heavier door if they are to be brought to rest at the same time. In order to accomplish this, I have included compensating resistors CR1 and CR2 in the armature circuits of the corridor door motor 29 and the car door motor 10 in connection with the 25 checking resistors.

30 35 Fig. 6 illustrates more clearly than Fig. 4 how the checking resistors and the compensating resistors are disposed in the armature circuits. The feed for the door motor armatures occurs at the junction point A. The opening door check resistors R1 and R2 may be closed by contact members 72 and 73. Then the checking resistance value effective on the corridor door motor A29 is X plus 40 R1—R2, while that effective on the car door motor A—10 is Y plus R1—R2. By moving the junction point F toward the junction point A, the corridor door will be checked less and the car door more. In a similar way, 45 the closing door check resistors R3—R4 are connected at another junction point G which may be adjusted to effect simultaneous checking of the doors as they close. With the construction, the system, after it is installed, 50 may be readily adjusted to suit any variation in the weights and operation of the doors.

55 A controller 55 is provided for including the resistors R1 to R5 in the door-motor circuits, for disconnecting the motors when the doors reach the end of their travel, and for preparing circuits through which the motors may be reversed.

60 65 The controller 55 comprises a cam shaft

56, a plurality of cam-shaped actuating members 57 to 63, inclusive, carried by the cam shaft, a plurality of contact fingers 64 to 70, inclusive, disposed to be moved into and out of engagement with a plurality of cooperating contact members 71 to 77, inclusive, by the cam-shaped actuating members, and a control motor 78 for rotating or rocking the cam shaft.

70 75 Referring now to Figs. 2 and 3, which illustrate the mechanical structure of the controller 55, the cam shaft 56 is supported in a pair of end bearings 80 and 81 mounted upon a base plate 82. The control motor 78 is also mounted at one end of the cam shaft on the base plate 82 and is connected to the shaft by means of a worm gear 83. The worm gear is preferably designed to operate the cam shaft at a speed much lower than that of the control motor.

80 85 As shown in Fig. 3, the contact finger 64 is pivotally mounted upon a finger support 85 and is held, by a pin 86, in position to cooperate with the contact stud 71 in closing a circuit. A compression spring 87 is disposed between the upper end of the pin 86 and the upper face of the contact finger to hold the contact finger in close contact with the contact stud when in closed position. The finger support 85 is pivotally mounted upon a support bracket 88 which is secured to the base plate 82 at one side of the cam shaft. A pin 89 and a compression spring 90 are employed for holding the finger support in its correct position upon the support bracket and for biasing it toward the contact stud 71.

90 95 An insulating block 91 is attached to the underside of the finger support 85. Attached to the insulating block is a wearing plate 92 that extends downwardly into the path of the cam member 57 in such manner that rotation of the cam member will raise the finger support against the opposition of the compression spring 90 and thereby disengage the contact finger 64 from the contact stud 71. The other contact fingers are mounted to be actuated by their cooperating cam members in a similar manner.

100 105 The cam members carried by the cam shaft are divided into two groups; the group on the right, bearing reference numerals 61, 62 and 63, being pinned permanently to the shaft, and the group on the left, bearing reference numerals 57, 58, 59 and 60, being permanently pinned to a sleeve or seating member 93 disposed on the cam shaft 56. A flange 94 is provided on the left-hand end of the sleeve 93 in position to face a flanged member 95 110 which is permanently pinned to the shaft 56 so that the sleeve and the cam members thereon will be driven with the shaft when the flanges are connected, as by a bolt 96.

115 120 125 130 The flanged member 95 is provided with

18 a series of holes around its periphery for the bolt 93, in order that the bolt may be removed from one hole, the sleeve and its cam members be rotated to a new position and the bolt be inserted in another hole to hold the sleeve in its new position. With this construction, the cam assemblies may be spaced a greater or lesser number of degrees apart and, therefore, inasmuch as the cam members control the insertion of the checking or decelerating resistance and the stopping of the motors when the doors reach the end of their travel, the apparatus may be readily adjusted to suit any particular installation.

19 The arrangement of the circuits is such that the control motor 78 rotates the cam members in the direction indicated by the arrows when the doors are being closed, and 20 in a reverse direction when the doors are being opened. By reason of the reduction gearing 83, the cam members travel much more slowly than the control motor and, in fact, never make a complete revolution but 25 simply rocks.

22 As shown in Fig. 2, a flange or cam member 100 is mounted upon, and pinned to, the right-hand portion of the shaft 56 in such manner that it will strike a block 101 and 25 limit the movement of the shaft when the doors are opened. As shown in Fig. 3, the end of the flange 94 is extended sufficiently 30 beyond the plate 96 to strike a block 102 and limit the movement of the shaft when the 35 doors are closed. It should be observed that the flange members 100 and 94 are integral parts of the cam groups and are adjusted with the cam setting.

38 The circuits of the door motors and the control motor are so connected that the three motors are energized simultaneously, with their field windings in parallel and their armatures in parallel but in series relation to the field windings. The effect of this interconnected parallel relation of the motors is that the corridor door and the car door will be opened or closed at the same speed, and that the control motor will follow the other motors approximately. Also, the control motor should be arranged to make slightly more revolutions than the door motors in order to insure that a sluggish door completes its travel. This operation of the control motor may be effected by so setting the cam members that the power for the motors will not be cut off until a short time after the doors are closed.

45 In case a door becomes stalled during its movement, the control motor continues to advance at a reduced speed until the action of the cams cuts off the power. This gives protection against burning out of the door motors.

48 In accordance with my invention, the door-operating relays OP and CL, the control re-

lays 50 and 51, the controller 55, the control motor 78, the resistors R1 to R5, the compensating resistors CR1 and CR2 and the switches 52 and 53 are so constructed and disposed that they may be mounted in a group upon a switch board or panel 103. The switch board may be located at any suitable point, as in the pent house where it may be easily attended, when necessary. Another advantage of this construction is that a large percentage of the apparatus may be assembled upon the switchboard at the factory instead of at the place of installation.

55 The invention may be more readily understood by an assumed operation thereof.

Assuming that the car 3 is moving down the elevator shaft and that the car attendant conditions the car to make a stop at the fourth-floor landing, then the inductor control relay 50 will be deenergized, by reason 85 of the deenergization of the car system, with which it is connected, when the car is approximately two feet away from the landing.

80 The deenergization of the inductor control relay 50 closes its contact members and thereby completes a circuit for energizing the inductor coil 43 on the car to operate the inductor plate 45, which circuit extends from supply conductor L1, through conductor 105, the contact members of relay 151, inductor 95 106, the coil of relay 43 and conductor 107, to supply conductor L2.

90 The energization of the inductor coil 43 causes the armature 45 to be attracted to it as the car approaches the 4th-floor landing and 100 while it is still approximately 9 or 10 inches away from the landing. The movement of the armature 45 closes its contact members *a* and *b* and thereby partially prepares the 105 circuits of the armature and field of the motor 29 for operation.

95 As the car 3 approaches still closer to the landing, within about 7", for example, the control relay 51 is deenergized by the operation of the car-control system and closes its 110 contact members *b* to start the doors to open. The closing of the contact members *b* on the relay 51 completes a circuit for energizing the door-opening relay OP, which circuit extends from supply conductor L1, through 115 conductors 108 and 109, the contact members *b* of relay 51, conductor 110, the coil of relay OP, conductor 111, the contact members 71 and 64 of the controller 55 and conductor 112, to the supply conductor L2. The energization 120 of the relay OP causes its contact members *a* and *b* to close and its contact members *c* to open.

125 The closing of the contact members *a* and *b* of the door-closing relay OP completes a plurality of parallel circuits in series for energizing the corridor-door motor 29 at the 4th floor, the car-door motor 10, and the control motor 78, the circuit for the corridor-door motor 29 extends from the supply con- 130

ductor L1, through a choke coil 113, line resistance 114, conductor 115, junction point 116, conductors 117 and 118, the field winding of motor 29, the contact members *a* of 5 armature 45, conductors 119 and 120, junction point 121, conductor 122, conductors 122 and 123, the contact members *a* of relay OP, and conductor 124, junction point 125, conductors 126 and 127, the armature winding 10 of motor 29, conductor 128, the contact members *b* of armature 45, conductors 129 and 130, compensating resistor CR1, junction point 131, conductors 132, the contact members *b* of relay OP, and conductors 133 and 15 134, to supply conductor L2.

The field winding of the car-door motor 10 is now in parallel with the field winding 20 of the corridor-door motor 29, the circuit therefor extending from the junction point 116 on conductor 115, through conductor 136, the field winding of motor 10 and conductor 137, to the junction point 121 on conductor 122.

The field winding of the control motor 78 25 is also in parallel with the field windings of the corridor-door motor 29 and the car-door motor 10, the circuit therefor extending from the junction point 116 on the conductor 115 through conductor 138, the field winding of motor 78 and conductor 139 to a junction point 140 on conductor 133, thereby placing all of the field windings of the 30 motors in parallel with each other.

The armature winding of the car-door motor 10 is now in parallel with the armature winding of the corridor-door motor 29, the circuit therefor extending from the junction point 125, through conductor 142, the armature winding of car-door motor 10, conductor 143 and compensating resistor CR2 to the junction point 131.

The armature winding of the control motor 78 is also in parallel with the armature winding of the corridor-door motor 29, the circuit therefor extending from the junction point 125, through conductor 144, the armature of motor 78 and conductor 145 to the junction point 131, thereby placing all 45 of the armature windings of the motors in parallel with each other but in series with the field windings.

Inasmuch as the field windings of the motors are now connected in parallel, and the 50 armatures are also connected in parallel but in series with the field windings, as briefly shown in Fig. 5, the three motors will tend to operate at the same speed, whereby the corridor door and the car door will be opened 55 simultaneously, and the controller 55 will be operated, in accordance with the movement of the doors, to insert the checking resistors at the proper points, cut off the power to the motors after the doors have reached 60 their final open positions, and prepare the

circuits for reversing the motors to close the doors.

As the corridor door at the 4th floor and the car door move to their open positions by 70 operation of the corridor-door motor 29 and the car-door motor 10, the control motor 78 rocks the cam shaft and the cam members thereon in the direction indicated by the arrow. When the doors near the end of their travel, the cam member 59 turns to such position that it permits the contact finger 66 to engage the contact stud 73, thereby completing a circuit for including the resistor R2 in parallel with the armatures of the 75 motors; which circuit extends from a junction point 150 on conductor 124, through conductor 151, resistor R2, conductor 153, the contact members 73 and 66 of controller 55, conductors 154 and 155, the normally closed contact members *c* of relay CL and conductor 80 156, to a junction point 157 on the compensating resistor CR1. The resistance R2 is now in parallel with the armatures of the 85 motors and causes them to slow down as the doors approach their fully-open positions. 90

As the doors approach still closer to their 95 fully-open position, the control motor turns the cam shaft 55 to a position where the cam member 58 permits the contact finger 65 to engage the contact stud 72 to thereby complete a circuit for inserting the resistor R1 in parallel with the resistor R2, which circuit extends from conductor 151, through resistor R1, conductor 159 and contact members 72 and 65, to a junction point 160 on conductor 155. With both resistors R1 and R2 included in parallel with the circuit for the armatures of the door motors, as well as the control motor, the doors will slow down 100 at the close of their movement to such a degree that they will not slam. 105

If the doors are not checked simultaneously and one opens faster than the other, the junction point 157 on the compensating resistor CR1 may be adjusted to such position as will cause the doors to slow down together in opening. 110

As the doors are checked and come to a stop in their fully-open positions against their jams or frames, the door motors are stalled and stop operating. However, at this point the control motor 78 turns the cam shaft to such position that the cam member 57 lifts the contact finger 64 from the contact member 71 and thereby opens the circuit that maintains the door-opening relay OP in an energized condition. The deenergization of the door-opening relay OP opens its contact members *a* and *b*, thereby cutting off the power to the corridor-door motor, the car-door motor and the control motor almost immediately after the doors reach their fully-open position. The final movement of the cam shaft also turns the cam member 63 to such position that it permits the contact 120 125 130

finger 70 to engage the contact member 77, thereby preparing a circuit for reversing the motors to close the doors.

Assuming now that passengers have 5 boarded the car at the fourth floor and that the car attendant has operated the car switch CS to cause the car to continue its down trip, then the contact segment *a* of the car switch will engage the cooperating contact members *b* and *c* and thereby complete a circuit for energizing the control relay 51 to cause the doors to close, which circuit extends from supply conductor L3, through the coil of relay 51, conductor 165, contact members *c*, *a* and *b* of car switch CS and conductor 166, to the supply conductor L4.

The energization of the control relay 51 closes its contact members *a* and thereby completes a circuit for energizing the door-closing relay CL, which circuit extends from supply conductor L1, through conductor 108, the contact members *a* of relay 51, conductor 167, the coil of relay CL, conductor 168, the contact members 77 and 70 of controller 55 and conductors 169 and 112, to the supply conductor L2.

The energization of the door-closing relay CL closes its contact members *a* and *b* and thereby completes a circuit for energizing the 30 corridor-door motor and the car-door motor to close the doors, and the control motor to control the closing operation. The circuit for the motors extends from the supply conductor L1, through the field windings of the motors, in parallel, as previously described, to the junction point 121 on conductor 122, thence, through conductors 122 and 170, to the contact members *a* of the door-closing relay CL and conductors 171 and 132, 35 to the junction point 131, where it divides and extends, in a reverse direction to that previously described, through the armatures of the corridor-door motor 29, the car-door motor 10 and the control motor 78, in parallel, to the junction point 125 on conductor 124 and 40 thence, through the conductors 124 and 172, the contact members *b* of door-opening relay CL, conductor 173, the contact members 67 and 74 of controller 55 (closed by reason of 45 the position of the cam member 60) and conductors 174 and 134, to the supply conductor L2.

As indicated, the field windings of the motors are energized in the same direction as 55 when the doors were being opened but the circuit through the armatures of the motors is now reversed in direction from what it was when the doors were being opened, thereby causing the door motors to reverse their 60 direction of operation and close the doors and the control motor to reverse its direction of operation and rock the cam shaft in a direction opposite to the arrow.

As the closing doors accelerate in their 65 movement, they reach a position where the

safety resistances R5 is brought into operation to prevent the doors from gaining a dangerously high speed at the center of their travel in closing. The safety resistance R5 is brought into operation at this point by the 70 control motor rotating the cam shaft of the controller to the position where the cam member 60 lifts the contact finger 67 from the contact member 74, thereby opening the shunt circuit around the resistor and inserting it 75 directly in circuit with the motors to keep the speed of the doors, in closing, within safe limits.

As the doors approach their fully-closed positions, the control motor turns the cam 80 shaft to such position that the cam member 61 permits the contact finger 68 to engage the contact member 75, thereby completing a circuit to insert the checking resistor R3 85 in parallel with the armatures of the motors to check the speed of the doors, which circuit extends from the junction point 150 on conductor 124, through conductor 151, resistor R3, the contact members 75 and 68, conductor 175, the contact members *c* of relay OP 90 and conductor 176, to a junction point 177 on the compensating resistor CR2.

As the doors approach still closer to their fully-closed position, the control motor rotates the cam shaft to such position that the cam member 62 permits the contact finger 69 95 to engage the contact member 76 and thereby includes the resistor R4 in in parallel with the resistor 23 to effect such further checking action on the doors as will cause them to close 100 easily without slamming.

If the doors are not checked simultaneously and one closes faster than the other, the junction point 177 on the compensating resistor CR2 may be adjusted to such a position as 105 will cause the doors to slow down together in closing.

After the doors are closed, the control motor continues its rotation for a very short distance until the cam member 63 on the controller moves into such position that it raises the contact finger 70 from the contact member 77, thereby opening the circuit for the door-closing relay CL and deenergizing it. The deenergization of the relay CL opens its 110 contact members *a* and *b* and thereby disconnects the motors from their source of power.

It should be noted at this point that the 115 operation of the controller 55 has moved the cam member 57 to such position that the contact finger 64 engages the contact member 71 and, therefore, that the circuit for energizing the door-opening relay OP is now so prepared that deenergization of the control relay 50 at any time will close its contact members 120 *b* and thereby effect the operation of the door-opening relay OP to open the doors.

By reason of the assumed operation of the 125 apparatus, it is seen that I have provided a 130

door-operating system in which the parts may be readily assembled in such positions that they may be most economically operated and maintained; that the parts of the apparatus in the system may be manufactured and assembled at the factory to suit a wide number of installations, and that, after the assembled parts are placed in an elevator installation, they may be readily adjusted to suit the particular characteristics of that installation, thereby effecting a large saving in manufacturing and assembling costs

Furthermore, it will be seen that the apparatus carried by the car is reduced in size and weight to a minimum, thereby effecting a saving in the operation of the car.

Although I have illustrated and described only one specific embodiment of my invention, it is to be understood that various changes and modifications may be made therein without departing from the spirit and scope of my invention.

I claim as my invention:

1. A door-operating system for an elevator having a car operable past a corridor door comprising a motor for operating the corridor door, a motor for operating the car door, a control motor, means for simultaneously energizing said motors, and a controller operated by said control motor for stopping said motors after a predetermined operation thereof.

2. A door-operating system for an elevator having a car operable past a corridor door comprising a motor for operating the corridor door, a motor for operating the car door, a control motor disposed remotely from the hatchway-door motor and the car-door motor, means for simultaneously energizing said motors, and a controller operated by said control motor for stopping said motors after a predetermined operation thereof.

3. A door-operating system for an elevator having a car operable past a landing comprising a motor disposed at the landing for operating the hatchway door thereat, a motor disposed on the car for operating the car door, a control motor disposed in the elevator pent house, means for simultaneously energizing said motors, and a controller operated by the control motor for stopping said motors after a predetermined operation thereof.

4. A door-operating system for an elevator having a car operable past a corridor door comprising a motor for operating the corridor door, a motor for operating the car door, a control motor, means operably responsive to stopping of the car at the corridor door for simultaneously energizing said motors, and a controller operated by said control motor for stopping said motors after a predetermined operation thereof.

5. A door-operating system for an elevator

having a car operable past a corridor door comprising a motor for operating the corridor door, a motor for operating the car door, a control motor disposed in a position remote from said door motors, means for simultaneously energizing said motors, means for decelerating the speed of said motors, and a controller operated by said control motor for connecting said decelerating means to said motors to reduce the speed of the doors at a predetermined point in their travel and for stopping the motors after a predetermined operation thereof.

6. In a door-operating system for an elevator having a car operable past a corridor door, a motor for operating the corridor door, a motor carried by the car for operating the car door, a control motor, means for simultaneously energizing said motors, means for decelerating the speed of said motors, a controller operated by said control motor for connecting said decelerating means to said motors and for stopping the motors after a predetermined operation thereof, and a panel having the control motor, the controller and the decelerating means being so mounted as to be located, as a unit, at a position remote from the corridor-door motor and the car-door motor.

7. In a door-operating system for an elevator having a car operable past a corridor door, a motor disposed adjacent to said corridor door for operating it, a motor carried by the car for operating the car door, a control motor, means for simultaneously energizing said motors, means for decelerating the speed of said motors, and a controller operated by said control motor for connecting said decelerating means to said motors, for stopping the motors after a predetermined operation thereof and for preparing a circuit whereby the motors may be energized for operation in the opposite direction.

8. In a door-operating system for an elevator having a car operable past a plurality of corridor doors, an operating motor for each corridor door, means operably responsive to the operation of the car, for selecting and preparing a circuit for the corridor-door motor, a motor carried by the car for operating the car door, a control motor, means for simultaneously energizing the selected one of the corridor-door motors, the car-door motor and the control motor, means for decelerating the speed of said motors, and a controller operated by said control motor for connecting said decelerating means to said motors, for stopping said motors and for preparing a circuit whereby the motors may be energized for operation in the opposite direction.

9. A door-operating system for an elevator having a car operable past a corridor door, a motor for operating the corridor door, a motor carried by the car for operating the car

door, a control motor, means for simultaneously energizing the motors, a rotatable shaft operated by said control motor, a group of actuating members firmly affixed to said shaft 5 in position to operate a group of cooperating contact members for decelerating and stopping said motors in one direction, a sleeve mounted on said shaft, a second group of actuating members disposed on said sleeve in 10 position to operate a second group of cooperating contact members for decelerating and stopping said motors in the opposite direction, and means for firmly securing the sleeve in any one of a plurality of positions on said 15 shaft to vary the relative operation of the motors to suit the elevator doors in connection with which they are installed.

10. A door-operating system for an elevator having a car operable past a corridor 20 door, comprising an electric motor disposed adjacent to said corridor door for operating it, an electric motor carried by the car for operating the car door, a control motor, a circuit for said motors, a compensating resistor disposed in said circuit, means for connecting 25 said circuit to a source of electric power for simultaneously energizing said motors, a checking resistor and means operably responsive to the operation of the control motor for 30 connecting the checking resistor in the circuit for the armatures of said corridor-door motor and said car-door motor to check the final movement of said doors, one end of said 35 checking resistor being adjustably connected to said compensating resistor whereby the checking effect on the doors may be varied to cause them to reach the end of their travel substantially simultaneously.

40. 11. A door-operating system for an elevator having a car operable past a corridor door, comprising a motor for operating the corridor door, a motor carried by the car for operating the car door, a control motor, a circuit for said motors, means for connecting 45 said circuit to a source of electric power for simultaneously energizing said motors to open or to close said doors, a compensating resistor disposed in series with the armature of the corridor-door motor, a compensating resistor disposed in series with the armature of the car-door motor, a plurality of checking resistors, means operably responsive to the operation of said control motor in one direction 50 for connecting one of said checking resistors in said circuit for checking the opening movement of said doors, and means operably responsive to the operation of said control motor in an opposite direction for connecting the other of said checking resistors in 55 said circuit for checking the closing movement of said doors, said checking resistors being adjustably connected to said compensating resistors whereby the checking effect on 60 the doors may be varied to cause them to reach 65

the end of their travel substantially simultaneously.

In testimony whereof, I have herunto subscribed my name this first day of May, 1931.

HAROLD V. McCORMICK.
